(57) **CLAIM**

The ornamental design for an accessory to put on a body, as shown and described.

DESCRIPTION

FIG. 1 is a front view of an accessory;
FIG. 2 is a back view of an accessory;
FIG. 3 is a plan view of an accessory;
FIG. 4 is a bottom view of an accessory;
FIG. 5 is a right side of an accessory;
FIG. 6 is a left side of an accessory;
FIG. 7 is a longitudinal sectional view along 7—7 line of FIG. 1 showing the front view of an accessory;
FIG. 8 is a perspective view of an accessory; and,
FIG. 9 is a reference perspective view showing the usage state of an accessory.
It being understood that the break lines indicate that the chain continues uniformly along a length.
